Sherman P. Jewett, and
Francis H. Root, of Buffalo, N.Y.
Letters Patent No. 542. Dated Jan'y 25th 1853.

The schedule referred to in these Letters Patent and making part of the same

To all whom it may concern:

Be it known that we, S. P. Jewett, and F. H. Root,
of Buffalo, in the County of Erie, and State of New York, have invented or produced
a new and ornamental design for Elevated Oven Stoves, of which the following is a full,
clear and exact description, reference being had to the accompanying drawings which
form part of this specification and which represent the several ornaments that consti-
tute our newly invented design.

The front plate (A) of the fire-box is of parallelogrammic
form with mouldings along the edges and on the face thereof, near the top bearing the in-
scription "May Queen, No. 4". A furnace door B, is hinged near either end of the
plate A, the two doors meeting at the centre of the latter: each of these doors is ornamented
on its exterior with a pentagonal star a, projecting from a central disc b, surrounded by
slotted radii (c) whose combined extremities terminate in the plain margin of a panel of par-
allelogrammic contour, the shortest boundaries or edges of which are vertical. Each side of the
stove, at the entrance of an oven, is fitted with a similar door C, having the same orna-
ments.

2

As. 543

Another side door, D, is fitted at either end of the fire box; the ornaments on this door are similar to those on the doors already specified, consisting of a pentagonal star projecting from a central disc and surrounded by fluted radii which terminate in the margin of a parallelogramic panel of slightly different proportions from those of the panels of the doors B and C. The ornaments of the several doors are bounded by beads or fillets, e, connected by a cavetto, f, the configuration of which is shown in profile on the door D, in connection with the profile of the front jamb of the said door. Mouldings ornament the edges of the side plates on which the doors C, and D are hung; these plates are shaped according to the length and direction of the flue. The stove is surmounted by an elevated oven whose base is surrounded by a moulding, d, and its front plate (E) is ornamented at its centre with an oval, floral device consisting of leaves surrounding a centre ornament, g, and surrounded by fluted radii, h, whose outer ends form a panel i, of elongated form under and over which are sloping inverse panels or oblong recesses K. K. The top of the oven is ornamented at its edges with a milled or ribbed border; to the side or end plates F, of the oven is hinged or hung a door G, having a pentagonal star m, projecting from a disc n, at the centre of the door and radial folds or projections o, surrounding the said disc and varying in lengths which terminate in the margin of a panel narrowest at its lower end and with four rounded corners, a moulding of similar figure or outline surrounding the said panel, the profile of which moulding consists of an ordinary combination of ovolos, a cimasecca and cavetto.

Having thus described our ornamental design for Elevated Oven Stoves, what we claim as new therein and desire to secure by letter patent, is the configuration and arrangement of the ornamental design of the plate B, as shown and described.

In testimony whereof we have hereunto subscribed our names,
